(57) **CLAIM**

The ornamental design for a selectively inflatable evacuation and rescue bag, as shown and described.

DESCRIPTION

The patent or application file contains at least one drawing executed in color. Copies of this patent or patent application

publication with color drawing(s) will be provided by the Office upon request and payment of the necessary fee.

FIG. 1 is a front and top perspective view of an embodiment of a selectively inflatable evacuation and rescue bag showing my new design in an uninflated condition;

FIG. 2 is a front and bottom perspective view thereof and illustrating a selectively openable and closable manual air valve through which the bag may be selectively inflated and deflated, as well as a selectively activatable lanyard and associated valve;

FIG. 3 is a top view thereof;

FIG. 4 is a bottom view thereof;

FIG. 5 is a left side view thereof;

FIG. 6 is a right side view thereof;

FIG. 7 is a rear view thereof;

FIG. 8 is a front view thereof;

FIG. 9 is a second front and top perspective view thereof in an open/unzipped condition illustrating an interior thereof;

FIG. 10 is a third front and top perspective view thereof in a closed/zipped and inflated condition;

FIG. 11 is a front and bottom perspective view of the bag of FIG. 10;

FIG. 12 is a top view of the bag of FIG. 10;

FIG. 13 is a bottom view of the bag of FIG. 10;

FIG. 14 is a left side view of the bag of FIG. 10;

FIG. 15 is a right side view of the bag of FIG. 10;

FIG. 16 is a rear view of the bag of FIG. 10;

FIG. 17 is a front view of the bag of FIG. 10; and,

FIG. 18 is a fourth front and top perspective view of a blaze orange embodiment of the bag of FIG. 1.

The evenly broken lines in the figures depict portions of the selectively inflatable evacuation and rescue bag that form no part of the claimed design. In FIG. 18, the unevenly dashed lines depict additional features that form no part of the claimed design.
